BAG FILLING DEVICE

Eduard W. Vredenburg, Berkeley, Calif.

Application April 24, 1943, Serial No. 484,400

1 Claim. (Cl. 226—48)

This invention relates to bag filling devices and particularly to a device for filling bags of the valve type in which the bag is sewn at each end and includes a filling valve in the side through which the bag is filled, the valve being subsequently inserted or folded to seal the bag contents.

Bag filling is normally conducted from a hopper on which a spout is provided, the bag being mounted upon the spout and material from the hopper discharged through the spout into the bag under the control of some feed control mechanism. To ensure that material passage from the hopper through the spout into the bag would be rapid and positive, various mechanical feeding devices have been utilized, such as rotating screws, worms and fans. These further complicate the structure since their operation must be controlled. Gravity feed of many materials has not been successful because of the peculiar characteristic of these materials, particularly when in finely divided form, to pack and lump in the filling spout.

The present invention is concerned with a novel improved bag filling device and it is in general the broad object of the present invention to provide a novel structure of this type enabling materials to be discharged rapidly and positively from a hopper through the spout and into a bag, particularly one of the valve type.

I have found that the greatest rapidity of discharge from the hopper is secured if the spout employed for filling the container has a continuous connection with the bottom of the hopper. One would ordinarily expect that it would be ample to place a spout at the lowermost point in the hopper and to permit material to discharge from this spout. However, in practice I have found that if the spout is connected completely across the hopper bottom, the greatest rate of discharge can be secured. Further, I have found that, particularly in the case of valved bags, the filling spout should be open to permit ready release of air. Even though the spout is seemingly completely filled with material rushing rapidly from the hopper through the spout, filling of the container is increased materially by an open ended spout.

The invention includes other objects and features of advantage, some of which, together with the foregoing, will appear hereinafter wherein the present preferred form of machine of this invention is disclosed.

In the drawings accompanying and forming a part hereof,

Figure 1 is a front elevation, partly cut away to illustrate certain details of construction.

Figure 2 is a side elevation of the machine shown in Figure 1.

Referring to Figure 1 I have provided a suitable frame indicated generally at 6 for supporting the weighing beam 7 in pivot blocks 8. The weighing beam has the form and configuration generally shown at 21 in Figure 3 in my Patent 2,314,299. A counterbalance 9 is hung on one end of the beam while a hopper structure generally indicated at 11 including a hopper 18 mounted by pivot blocks 12 on pivots 13 at the other end of the weighing beam. This type of mounting is shown and described in my aforesaid patent.

To provide for feed of material, a container 16 is provided above the hopper structure 11 in a position to discharge through opening 17 into hopper 10. A movable gate 18 is mounted on shaft 19 and is oscillated across opening 17 by handle 20 secured to shaft 19. Normally handle 20 is rocked counterclockwise (Figure 2) by an operator until lever 22 on shaft 19 has moved across arcuate face 23 on lever 24 until it drops into notch 26.

The lever 24 is hinged intermediate its ends at 27 on a member 28 which is mounted on one side of the frame. The lever 24 is free to rock counter-clockwise to admit the end of lever 22 into the notch; its clockwise movement is restricted by stop 29. An extension 31 is carried on the weighing beam below the extending end 32 of lever 24. This serves to release the engagement of lever 22 and notch 26, enabling counterweight 33 on shaft 19 to rock the shaft and gate 18 clockwise and shut off material flow.

The hopper 10, as appears in Figure 1, tapers in toward its bottom to direct the flow of material into filling spout 34 through a slot 36 which extends completely across the hopper bottom. The spout 34 is generally circular in cross section and projects angularly across the hopper bottom to direct flow downwardly through its first or discharge end 37 into a suitable container. In Figure 2 I have shown the spout discharging into a valved bag 38. The upper or second end 39 of the spout preferably extends beyond the end of slot 36; this end is left open to the atmosphere. The slot connection between the hopper and spout and the open ended spout enable a very high rate of discharge to be maintained from the hopper through the spout and into a container.

To support the container and retain it in posi-

tion plates 41 are secured on each side of the hopper structure 11. Arms 42 are connected to the plates, the arms depending from the plates to support a rest 43 for a container which is positioned between the arms. The distance between the rest 43 and the spout 34 is adjusted to suit the size of container being filled. This is achieved in the machine shown by providing side arms 46 on each side of the rest and connecting these by removable bolts 47 at desired points. The ends of arms 42 are guided by hinged links 48 connected to the arms and to the frame 6 to prevent the hopper structure and the rest from swinging about pivots 13.

Suitable means are provided for retaining a container in filling position. The novel mechanism shown is particularly adapted for use with a valved bag. This includes a bell crank 51 mounted at 52 between angle irons 53 secured on the front of hopper 10. One end 54 of the bell cranks is formed as a handle while the other end 56 is faced with rubber 57 and is curved to fit over the valve portion 58 of a bag, and hold it securely against the spout. To hold the bell crank in bag retaining position, a toggle 59 is connected between the handle portion of the bell crank and the angle irons. This toggle is readily broken by an operator rocking handle 54 clockwise to release a bag, the toggle rocking inwardly to permit the bell crank to move. When another bag is positioned and handle 54 is rocked counterclockwise, the toggle moves into its locking position, that shown in Figure 2.

In operation, with a bag in position and a supply of material available in container 16, an operator rocks the handle 20 to latch the gate 18 open. Material flows freely into hopper 10, through the spout and on into the container or bag. When the weight of material in the hopper and in the bag equals that to be weighed out, or very nearly so, the beam 7 moves up and extension 31 moves lever 24 to release lever 22. The gate then swings shut. The material continues to flow from the hopper 10 but since most of it has already entered the bag, little further time is required before the bag can be removed and another placed in position.

I claim:

A device for feeding a free-flowing powdered material into a bag sewn at each end and having a filling valve in the side thereof; said device consisting of a tubular member of circular cross section, said member having its first end formed for insertion into the filling valve portion of a bag, the second end of said member being open to the atmosphere, said member having a slot formed intermediate said ends of a width less than the diameter of said member; and a hopper joined to said member along the boundaries of said slot and supporting said member with the first end lower than the second end, said second end being elevated with respect to the upper end of said slot.
